UNITED STATES PATENT OFFICE.

GUSTAVE JOASSART, OF LIEGE, BELGIUM.

DESIGN FOR A MOTORCYCLE-FRAME.

57,976.

Specification for Design.

Patented May 24, 1921.

Application filed July 8, 1920. Serial No. 394,837. Term of patent 14 years.

To all whom it may concern:

Be it known that I, GUSTAVE JOASSART, a subject of the King of the Belgians, residing at Liege, Belgium, have invented a new, original, and ornamental Design for a Motor-cycle-Frame, of which the following is a specification, reference being had to the accompanying drawing, forming part thereof.

The figure is a side elevation of a motor-cycle frame, showing my new frame design in full lines, the parts of the motor-cycle

other than the frame appearing in dotted lines.

I claim:

The ornamental design for a motor-cycle frame, as shown.

In testimony whereof I affix my signature in presence of two witnesses.

GUSTAVE JOASSART.
